UNITED STATES PATENT OFFICE.

HERMANUS FRANCISCUS TOL, OF THE HAGUE, NETHERLANDS, ASSIGNOR TO NAAM-
LOOZE VENNOOTSCHAP MACHINEFABRIEK "REINEVELD," OF DELFT, NETHER-
LANDS, A CORPORATION OF NETHERLANDS.

IRONING MACHINE.

Application filed February 10, 1927, Serial No. 167,246, and in the Netherlands July 21, 1926.

The invention relates to ironing machines of the type in which a flat iron is adapted to reciprocate over a table, said iron being supported by an arm or other supporting member travelling along a guide member.

The object of the invention is to provide improved means for increasing and regulating the pressure between the iron and the table and for lifting the iron, during its movement over the table.

To attain this end according to the invention the guide member along which the arm travels is movably mounted in the frame of the machine in such a way, that the iron may be lifted from or pressed to the table.

Moreover the iron may travel along the arm by which it is supported transversely to the direction of the table, so that a table may be used which is wider than the iron moving over it.

This feature, known in itself, has in combination with the construction as mentioned above, the advantage that the iron may be also displaced transversely without being in contact with the table.

In order that the invention may be more fully understood reference will be made to the accompanying drawing in which an ironing machine according to the invention is illustrated diagrammatically by way of example.

Fig. 1 is a side elevation of the machine.

Fig. 2 is a plan view of the machine.

Fig. 3 is a diagrammatic view of the parts for lifting and pressing the iron.

The flat iron 1 is suspended from a carriage 2 which by means of rolls 3 may travel in the arm 4 transversely to the direction of the table 5.

The arm 4 is provided with a rear part 6 having rolls 7 with a vertical shaft and rolls 8 with a horizontal shaft. By means of these rolls the arm 4 may travel in a longitudinal direction in a frame work 9, the beams of which form the guides for the rolls.

The reciprocating movement of the arm 4 with the iron 1, is obtained in the known manner by means of a belt 10 which travels constantly over the pulleys 11 and 12, carried by shafts 13 and 14 bearing in suitable brackets 15 and 16 attached to the frame of the machine. On the shaft 14 is fixed the driving pulley 17.

For transmitting the movement from the

belt to the arm use is made of a well known (not shown) clutch, such as disclosed in Patent No. 1,431,279 to Baker, the coupling of which is effected by a handle 18 and a shaft 19.

The frame 9 is provided at the ends with two horizontal pivots 20 bearing in the frame of the machine.

In order to move the frame 9 together with the arm 4 and the iron 1, the frame is connected with two rods 21.

These two rods 21 are connected with two horizontal levers 22, swingable about a shaft 23 and interconnected by a treadle 24. In pushing the treadle 24 the rear end of the frame 9 is lowered and the iron lifted from the table. Free rotatably about the same shaft 23 are arranged two other horizontal levers 25 interconnected by a second treadle 26. Said levers 25 are connected by rods 27 with balance arms 28 having their fulcrum 29 attached to the machine frame. At one side said balance arms 28 are provided with an adjustable weight 30, at the other end they are connected with the levers 22 by rods 31. In pushing the treadle 26 the balance arms 28 are moved, the rods 31 and the levers 22 are pulled upwardly and the iron 1 is pressed upon the table.

In its normal position the iron is pressed upon the table by its own weight and by the force effected by the weights 30 acting on the balance arms 28. It will be seen therefrom that in varying the distance of the weights 30 from the fulcrum 29 one may adjust to some extent the normal pressure of the iron upon the table.

In Fig. 2 of the drawing it is clearly shown, that the table 5 is much wider than the iron 1, whereas in the known constructions of this type of machines the width of the table was practically limited by the width of the iron.

Having now particularly described and ascertained the nature of the invention, and in what manner the same is to be performed I declare, that what I claim is:

1. An ironing machine comprising a stationary table; a reciprocating iron-support; a mechanism for imparting a reciprocating motion to said support; a guide member parallel to the table along which said support may travel pivotally mounted in the frame of the machine so as to swing around an axis parallel to the table; and means for moving

said guide member so as to lift the iron from the table and to control the effective pressure between the iron and the table.

2. An ironing machine comprising a table; 5 a mechanism for imparting a reciprocating motion to an iron; a supporting member along which the iron may travel transversely to the direction of the table; a guide member along which said supporting member may 10 travel in a direction parallel to the table; means for movably connecting said guide member with the frame of the machine; and means for moving said guide member, so as to lift the iron from the table and to control 15 its effective pressure upon the table.

3. An ironing machine comprising a table; a mechanism for imparting a reciprocating motion to an iron; an arm along which the iron may travel transversely to the direction 20 of the table, a guide member for said arm pivotally connected with the frame of the machine so as to swing around an axis parallel to the table; a treadle for swinging the guide member in a direction causing a lifting of the 25 iron from the table and a treadle for swinging the guide member in the opposite direction causing an increase of the effective pressure of the iron upon the table.

4. An ironing machine comprising a stationary ironing table; a mechanism for imparting a reciprocating motion to an iron; a carriage from which said iron is suspended; an arm mounted transversely to the direction of the table and provided with tracks along which said carriage may travel; a longitudinal guide member for supporting said arm, pivotally connected with the frame of the machine and swingable about an axis parallel with the table; tracks on said guide member along which the arm may travel by means of 30 rolls rotatably mounted in the rear part of said arm; and means for swinging the guide member about its axis. 35

5. An ironing machine comprising, in combination; a table; an iron; supporting means permitting the iron to be moved in a longitudinal direction in the plane of the table; supporting means permitting the iron to be moved in a transverse direction in the plane of the table; means for reciprocating the iron in one of said directions; and means for varying the pressure of the iron upon the table and 40 for lifting it from the table. 45

In testimony whereof I affix my signature.

HERMANUS FRANCISCUS TOL.
